UNITED STATES PATENT OFFICE.

ROBERT M. GALBRAITH, OF PINE BLUFF, ARKANSAS.

DESIGN FOR A DRAW-BAR HOUSING.

SPECIFICATION forming part of Design No. 27,219, dated June 15, 1897.

Application filed April 29, 1897. Serial No. 634,480. Term of patent 14 years.

To all whom it may concern:

Be it known that I, ROBERT M. GALBRAITH, a citizen of the United States, residing at Pine Bluff, in the county of Jefferson, State of Arkansas, have invented a certain new and original Design for Draw-Bar Housings, of which the following is a full, clear, and exact description, reference being had to the accompanying drawings, forming a part of this specification, wherein—

Figure 1 is a perspective view of my newly-designed draw-bar housing, looking from in front and above; and Fig. 2 is a similar view, but looking from below.

This invention relates to a new and original design for draw-bar housings; and it consists in the shape and ornamentation of the same, as will hereinafter more clearly appear.

In the drawings, A indicates a rectangularly-shaped plate, whose corners are slightly rounded.

B indicates a lip or flange extending up from the front edge of this plate A, which flange, as shown, does not extend entirely across the plate.

C indicates projections, of which there are

two, arranged on the upper face of the plate A and consisting of three walls, the front wall being perforated or formed with an opening, as shown. The side walls are curved rearwardly to meet the plate A.

D indicates an angular projection or pocket on the under side of the plate A, which is formed by two side walls and a bottom wall, the plate A forming the top wall. The side walls of this projection are formed with longitudinally-disposed slots or openings, as shown more clearly in Fig. 2.

E indicates wings extending from the rear end of projection D, said wings having a curved portion e, which meets the lower face of plate A, as shown.

What I claim is—

The design for a draw-bar housing, substantially as herein shown and described.

In testimony whereof I hereunto affix my signature, in presence of two witnesses, this 30th day of March, 1897.

ROBERT M. GALBRAITH.

Witnesses:

E. C. LAINE,

P. SOUTHER.
